STEP PLATFORM BUMPER

Frank J. Oliver, Jr., Jacksonville, Fla.

Application October 19, 1955, Serial No. 38,447

Term of patent 14 years

(Cl. D14—6)

FIG. 1.

FIG. 2.

Figure 1 is a plan view of the step platform bumper showing my new design; and

Figure 2 is a rear elevational view.

I claim:

The ornamental design for a step platform bumper, as shown.
